UNITED STATES PATENT OFFICE.

SYLVANUS C. HOPKINS, OF BOSTON, MASSACHUSETTS.

SEAT FOR CHAIRS, SETTEES, AND VEHICLES.

SPECIFICATION forming part of Letters Patent No. 235,437, dated December 14, 1880.

Application filed December 4, 1879.

To all whom it may concern:

Be it known that I, SYLVANUS C. HOPKINS, of Boston, Massachusetts, have invented certain Improvements in Seats for Chairs, Settees, and Vehicles; and I do hereby declare that the same are fully described in the following specification and illustrated in the accompanying drawings.

The object of these improvements is to strengthen, simplify, and cheapen chairs and other seats.

My invention relates to the parallel bars composing the seat-surface, to the transverse rails upon which said bars rest, and to the seat formed, as described, by the union of said parts.

My invention consists in the combination of devices, as set forth in the appended claims.

In the drawings, Figure 1 represents two transverse rails for a seat, and illustrates the process of forming them from a single piece of stock. Fig. 2 is a plan of a seat with some of the bars broken away to illustrate its connection with the leg-frames. Fig. 3 is a side view 25 of the seat as applied to a folding chair, and Fig. 4 a detail view of the same at the rear end.

My improved seat is composed of a series of parallel bars, *a*, resting upon and secured to 30 transverse rails *b*, which are formed with notches or grooves *c* in their upper edges, of suitable shape, size, and number to receive the bars *a*, laid therein sidewise. In the drawings these bars are cylindrical, and the 35 notches of a corresponding form, and I employ this shape almost exclusively because of its economy and simplicity. I sometimes split the bars longitudinally, making them semi-cylindrical, or nearly so, and insert them 40 in the half-round notches, as before. This gives a more even upper surface to the seat; but it is not so ornamental nor so strong, unless larger bars are employed.

I am accustomed to secure each bar in its 45 notch by driving a single corrugated nail through each end into the rail, as indicated in Fig. 2. The advantage of these notches is, that by their aid the seat-bars are held more firmly in place, and a much stronger seat is 50 produced than would be possible by nailing

bars of any shape on a plane surface, as is ordinarily done. My mode of construction is also much cheaper than where sockets are employed, into each of which the bars *a* are inserted endwise.

In constructing my improved seat I prefer to proceed as follows: I prepare stock of suitable dimensions and bore a series of holes of proper size in a line corresponding to the desired curve of the seat, then separate the 60 board into two parts by sawing along the line of the centers of these holes, thereby leaving one edge of each of the two parts notched with half-round recesses adapted to receive the cylindrical or semi-cylindrical seat-bars, which 65 may be rapidly and cheaply produced by well-known means, and efficiently held in their sockets by a single nail near each end.

The seat thus produced has a very neat rustic appearance, and, being so cheap and strong, 70 is well adapted for summer-houses, lawns, and piazzas. Short sections of bamboo, cane, or other wood in the natural state may be employed for the seat-bars *a*, and secured in the notches *c*.

Another feature shown in the drawings, but not original with me, relates to the means of connecting the seat to the leg-frames in the simplest manner. I perforate the cross-rails *b* at a suitable point, as at *d*, and pass through 80 such perforations the cross-round *e*, which, in its full size and strength, connects the legs *f* together and supports the front of the seat.

When the seat is applied to a folding chair, as in the drawings, this construction enables 85 the seat to swivel or fold against the back frame. If arranged for the back instead of the front of the seat to swivel, the holes would be near the back ends of the rails, and through them would pass the middle round of the back 90 or long posts of the chair. In a rigid chair both front and back holes would be employed for the rounds; but the seat would not swivel. Thus, without the castings, staples, screws, or hinges ordinarily required, or any other expense than the boring of the holes, and without weakening other parts of the chair, my 95 seat is permanently secured in position.

This construction also admits of all the posts being placed outside of the seat-rails without 100

changing the proper location of the rounds, which, in a folding chair with a scroll-shaped seat, is convenient to admit the front of the scroll to pass between the front posts, thereby 5 folding more compactly.

In using my seat in chairs employing a fabric back, I fasten the upper end of the fabric to the cross-slat connecting the tops of the rear posts, *g*, and nail the bottom of the fabric 10 to the rear bar, *h*, inserted endwise into and firmly secured in sockets *i*, through the edges of which cuts the rear end line of the rail *b*, so as to bring the periphery of the bar *h* into the plane of the end of the rails *b*.

15 The advantage of this construction is, that a fabric of the full width of the seat, or of the space between the posts *g*, may be used and nailed to the bar *h* its entire length without coming in contact with the rails *b*. In folding 20 chairs of any kind this bar forms a convenient handle for carrying the chair. It also gives a more neat and uniform appearance to the seat as a whole, and is stronger than a strip merely nailed to the end or bottom of the rails *b* for 25 the same purpose.

I make no claim to the folding frame shown in Fig. 3, except as to the construction and

combination therewith of the seat therein illustrated.

I disclaim the construction and mode of 30 uniting the parts shown in the Patent No. 80,528, granted to T. J. Close, July 28, 1868, as forming no part of my invention.

I claim as of my invention—

1. The improved seat herein described for 35 cars, settees, chairs, &c., embodying the combination of a series of parallel bars with two or more transverse rails formed with half-round grooves or notches, as described, across their upper edges, to receive the parallel bars side- 40 wise and permit their ends to project, said parts being nailed to each other at each intersection, substantially as set forth.

2. The combination, in a seat, of a series of parallel cylindrical bars projecting at each 45 end beyond the side rails, with two or more transverse rails having their upper surfaces shaped to the desired curvature of the seat, and provided with half-round recesses for the seat-bars, substantially as set forth.

SYLVANUS C. HOPKINS.
